CIGAR HUMIDOR

John G. Clarke, Toledo, Ohio, assignor to Owens-Illinois
Glass Company, Toledo, Ohio, a corporation of Ohio

Application November 19, 1954, Serial No. 33,163

Term of patent 7 years

(Cl. D85—2)

Fig. 1.

Fig. 1 is a top plan view of a cigar humidor, showing my new design;

Fig. 2 is an elevational view thereof;

Fig. 3 is an elevational view with parts in section taken from one side of the view in Fig. 2; and

Fig. 4 is a fragmentary sectional view taken along the plane of 4—4 of Fig. 3.

I claim:

The ornamental design for a cigar humidor, substantially as shown.
